UNITED STATES PATENT OFFICE.

JAMES R. CARDWELL, OF CHICAGO, ILLINOIS, ASSIGNOR TO UNION DRAFT GEAR COMPANY, A CORPORATION OF ILLINOIS.

FRICITION DRAFT-GEAR.

1,243,256.

Specification of Letters Patent. Patented Oct. 16, 1917.

Application filed September 25, 1915. Serial No. 52,690.

To all whom it may concern:

Be it known that I, JAMES R. CARDWELL, a citizen of the United States, and resident of Chicago, county of Cook, and State of Illinois, have invented certain new and useful Improvements in Friction Draft-Gears, of which the following is a specification, and which are illustrated in the accompanying drawings, forming a part thereof.

The invention relates to friction draft gear and more particularly to those having the friction elements confined by spring pressure which is exerted in a direction transverse to the line of draft. The object of the invention is to provide a friction draft gear of great efficiency and having a wide range of relative movement between the followers in proportion to the amount of linear compression of the spring.

In the accompanying drawings,—

Figure 1 is a central plan sectional view of a draft gear embodying the features of improvement provided by the invention and showing some of the associated parts of the underframe of a car partly in section and partly in plan.

Fig. 2 is a side view of the friction draft gear mechanism partly in section on the plane indicated by the line 2—2 on Fig. 1, a detail of one of the center sills of the car being also shown in side elevation, and

Figs. 3, 4 and 5 are perspective views showing some of the individual parts of the draft gear mechanism.

The center sills of a car are indicated at 10, 10, and the front and rear draft lugs at 11, 11 and 12, 12, respectively. The draft gear yoke is shown at 13 and a detail of the coupler at 14. In conformity with the usual practice in the mounting of draft gear of the type to which the invention relates, the two center sills 10, 10, are each provided with a slotted opening 15, for the reception of a transverse spring bolt 16. This bolt carries the draft gear springs 17, 17, and the spring followers 18, 18, of well known construction.

The front and rear followers for engaging the draft lugs 11, 11, and 12, 12, of the car, are represented at 19 and 20. Each of these followers is preferably of box-like construction with its inner end open and its two side walls notched, as at 21, Fig. 2, in line with the spring bolt 16, to permit the followers to close over the bolt when the gear

is compressed. The end wall of each of the followers 19, 20, is shod upon the inside with a friction block 22, having oppositely inclined beveled faces 23 and 24.

The draft gear further comprises a pair 60 of side plates 25, 26, each mounted on the spring bolt 16 next within one of the spring followers 18. Each has its two ends extended into the chambers of the box-like main followers 19, 20, and each side plate is centrally provided with an inwardly projecting portion 27 having oppositely inclined beveled faces 28 and 29. As shown, each of the side plates 25, 26, is of such length and width that its two ends contact with the end 70 walls of the main followers 19, 20, and its rear face contacts with the adjacent side walls of the two followers at the same time, that the inner ends of these followers come into contact during the closing of the gear. 75 The impact of closing is accordingly distributed among several contacting parts.

Intermediate wedge members 30, 31 and 32, are located between the friction shoe 22 at each end and the adjacent beveled surfaces 28, 28 or 29, 29, of the inwardly projecting portions 27 of the two side plates 25, 26. The wedge members 30 and 31, at each end, are preferably of triangular shape and each slides upon the inside face of the corresponding end portions of one of the side plates 25, 26, and upon the adjacent beveled face 23 or 24, of the corresponding friction shoe 22. Each of the wedge members 32, on the other hand, preferably extends across 85 the center line of the gear in one piece and has a tapering head, 33, 34, at each side. The two beveled surfaces of each of the heads 33, 34, of each of the wedge members 32, are accordingly in sliding contact with 90 the third face of one of the triangular wedge members 30 or 31, and with the adjacent beveled face 28 or 29, of the inwardly projecting portion 27 of the adjacent side plate 25 or 26. 100

Preferably the beveled contacting surfaces of the several friction elements are all so inclined that each makes only an acute angle with a line extending transversely through the gear. As shown, this angle of inclination is so small that direct longitudinal pressure of one of the wedges, as 32, against the contacting elements, as 27, would not serve to effect a relative lateral movement between these parts. Under these circumstances, only 110

a combined action of the two oppositely inclined faces of the friction elements, as 30 and 31, against the co-operating parts, as 22 and 32, is sufficient to accomplish relative 5 lateral movement and an effective frictional resistance to the movement is provided. On the other hand, the return movement of the parts, effected by pressure of the springs 17, 17, upon release of the gear, is facilitated 10 as it is accomplished by inward movement of the gradually tapering members, 30, 31 and 27. Furthermore, the large number of relatively movable friction elements provides a wide range of movement between the 15 front and rear followers 19, 20, in proportion to the combined outward movement of the two spring followers 18, 18. The arrangement also provides that each of the two friction shoes 22 comes into contact with the 20 adjacent wedge member 32 simultaneously with the contact of the followers 19, 20, with each other and with the side plates 25 and 26, during the closing of the gear.

I claim as my invention,—

- 25 1. In a draft gear, in combination, a pair of followers, a pair of laterally movable side plates, a plurality of inwardly facing wedges engaging each of the side plates, an outwardly facing wedge between each two adjacent inwardly facing wedges at each side, and a wedge element fixed with reference to each of the followers and engaging one of the first named wedges at both sides.
- 30 2. In a draft gear, in combination, a pair of followers, a pair of outwardly movable plates, springs opposing such outward movement, a plurality of pairs of laterally movable inwardly facing triangular wedges located between the followers bearing outwardly on the plates, the wedges of each pair having their axes upon a common transverse line, and outwardly facing wedges between the corresponding inwardly facing wedges of each two adjacent pairs.
- 35 3. In a draft gear, in combination, a pair of followers, two pairs of laterally movable inwardly facing wedges located between the followers, the wedges of each pair having their axes upon a common transverse line, a
- 40 4. In a draft gear, in combination, a pair of followers, a pair of laterally movable side plates, springs resisting outward movement of the side plates, three pairs of inwardly facing wedges arranged in a longitudinal series between the followers, the wedges of each pair having their axes upon a common transverse line, the wedges of the two end pairs being each in sliding engagement with the corresponding side plate and each of the wedges of the intermediate pair being fixed with reference to one of the side plates, a double ended transverse wedge element located between each two adjacent pairs of inwardly facing wedges with each of its ends engaging a wedge of both said pairs, and an additional wedge element fixed with reference to each of the followers and engaging both of the wedges of the adjacent pair.
- 45 5. In a draft gear, in combination, a pair of followers, a pair of laterally movable side plates, springs resisting outward movement of the side plates, three pairs of inwardly facing wedges arranged in a longitudinal series between the followers, the wedges of each pair having their axes upon a common transverse line, the wedges of the two end pairs being each in sliding engagement with the corresponding side plate and each of the wedges of the intermediate pair being fixed with reference to one of the side plates, a double ended transverse wedge element located between each two adjacent pairs of inwardly facing wedges with each of its ends engaging a wedge of both said pairs, and an additional wedge element fixed with reference to each of the followers and engaging both of the wedges of the adjacent pair.
- 50 6. In a draft gear, in combination, a pair of followers, a pair of laterally movable side plates, springs resisting outward movement of the side plates, three pairs of inwardly facing wedges arranged in a longitudinal series between the followers, the wedges of each pair having their axes upon a common transverse line, the wedges of the two end pairs being each in sliding engagement with the corresponding side plate and each of the wedges of the intermediate pair being fixed with reference to one of the side plates, a double ended transverse wedge element located between each two adjacent pairs of inwardly facing wedges with each of its ends engaging a wedge of both said pairs, and an additional wedge element fixed with reference to each of the followers and engaging both of the wedges of the adjacent pair.

JAMES R. CARDWELL.
